UNITED STATES PATENT OFFICE.

PERCY O. JUDSON, OF HACKENSACK, NEW JERSEY.

DESIGN FOR A FLOOR-COVERING.

44,171.

Specification for Design.

Patented June 10, 1913.

Application filed October 23, 1912. Serial No. 727,442. Term of patent 14 years.

To all whom it may concern:

Be it known that I, PERCY O. JUDSON, a citizen of the United States, residing at Hackensack, in the county of Bergen and State of New Jersey, have invented a new, original, and ornamental Design for Floor-Covering, of which the following is a specification, reference being had to the accompanying drawing, forming a part thereof.

The drawing shows a plan view of a section of the floor covering, the entire covering being made by repeats of the design shown in the drawing.

The present invention comprises a design for floor covering purposes composed of ornamental blocks, each block being formed as a square, as indicated by dotted lines in

the figure, with the line touching at two points of the figure upon each side and with certain parts cut out as complementary to other extended parts formed upon other blocks. The blocks are formed in a plurality of colors, and laid with a block of one color interlocking with a block of a different color, as indicated by the shading in the drawing.

I claim—

The ornamental design for floor covering as shown and described.

PERCY O. JUDSON.
